VARIABLE FREQUENCY OSCILLATOR

Wolcott Marsh Smith, Springfield, Mass., assignor, by mesne assignments, to General Instrument Corporation, Elizabeth, N. J., a corporation of New Jersey

Application October 31, 1946, Serial No. 706,949

18 Claims. (Cl. 250—36)

1

This invention relates to an oscillator circuit, the frequency of oscillation of which may be varied instantaneously and over a relatively wide range in a simple manner.

This type of circuit is of particular value in frequency modulation transmitters, in which the frequency of the transmitted signal must vary in accordance with and proportionately to the variations in frequency of the sound intelligence to be transmitted thereby. With the circuit of the present invention a variable frequency oscillator has been produced which is of exceedingly simplified and economical construction, which employs but a single vacuum tube, and which attains an exceptionally high sensitivity of output frequency to variations in applied voltage, the output amplitude retaining a high degree of amplitude stability. The circuit of this invention is susceptible of taking several forms, each of which will achieve a specific objective either with regard to sensitivity or direction of response, range of frequency variation, or constancy of output amplitude. In addition, the output resulting from this circuit has been found to be exceedingly rich in harmonics, so much so that the amplitude of the lower harmonics is quite comparable to that of the fundamental. As a result of this feature, the flexibility of use of the circuit is increased exceedingly.

This circuit is disclosed in a schematic or generalized way in Fig. 1 of the drawings appended hereto, Fig. 1 showing Z_g connected to G_2 ;

Figs. 1A and 1B are fragmentary reproductions of the schematic of Fig. 1, but showing Z_g connected respectively to the anode of tube V_1 and to the screen grids G_3 and G_5 ;

Figs. 2A, 2B and 2C represent alternative embodiments of Z_k of Fig. 1;

Figs. 3A, 3B, 3C and 3D represent alternative embodiments of Z_g of Fig. 1;

Figs. 4A, 4B, 4C and 4D represent alternative embodiments of Z_a of Fig. 1;

Figs. 5A, 5B, 5C and 5D represent alternative embodiments of Z_c of Fig. 1;

Figs. 6A, 6B, 6C and 6D represent alternative embodiments of Z_o of Fig. 1;

Figs. 7A, 7B, 7C and 7D represent alternative embodiments of Z_L of Fig. 1;

Figs. 8A and 8B represent alternative embodiments of Z_s of Fig. 1;

Figs. 9, 10, 11 and 12 represent various specific embodiments of the generalized circuit of Fig. 1, employing various combinations of the impedances shown in Figs. 2 through 8;

Fig. 13 is a graph showing the variation in sound.

2

peak amplitude of the output voltage of various circuits as the input voltage E_c is varied;

Fig. 14 illustrates the change in frequency of various circuits as the input voltage E_c is varied;

Figs. 15, 16 and 17 are similar to Fig. 14, but relate to different circuits;

Fig. 18 is a graph showing the variation in $-R$ as E_c is varied for various values of R_2 .

The circuit of the present invention involves

10 the use of but a single vacuum tube V_1 , which is here illustrated as having tube elements including a cathode 2, a plate 4, and a plurality of intermediate electrodes comprising a tube control grid G_1 , oscillator elements comprising an oscillator anode G_2 and an oscillator control grid G_4 , as well as screen grids G_3 and G_5 , and suppressor grid G_6 . Tubes having the standard designations 7A8, 6A8 and 7B8 have been found to be exceedingly suitable for use in this circuit, but other tubes

20 which can perform the functions hereinafter to be described may be substituted in their place. A plurality of biasing circuits for the tube elements are provided, these including Z_k for the cathode, Z_a for the oscillator anode G_2 , Z_o for the oscillator control grid G_4 , Z_s for the screen grids G_3 and G_5 , and Z_L for the tube anode 4. E_b represents a positive biasing voltage so chosen in conjunction with the biasing circuits as to cause negative transconductance to exist between the oscillator anode G_2 and the oscillator control grid G_4 . A coupling circuit Z_c is provided between the oscillator anode G_2 and the oscillator control grid G_4 , the impedance Z_c including a capacitor C_1 . E_c represents a suitable voltage source which applies a voltage to the tube control

30 grid G_1 , this voltage being variable by any convenient means between zero and negative quantities. The various impedances are so designed, as shall become clear hereafter, that the voltage E_o , the output voltage of the circuit, has a frequency 35 which is determined by and varies with the magnitude of the negative bias applied to G_1 by E_c . In discussing the operation of the circuit, E_c will generally be considered as having a definite value, and it will be noted that for different values of E_c , the frequency of E_o will differ. Consequently,

40 if a varying voltage is applied to E_c voltage, the amplitude of which is, for example, proportional at all times to the amplitude of a given sound, variations in E_c determined by the frequency of 45 the sound will be reflected in corresponding variations in the frequency of E_o . By this means, the frequency of E_o will be proportional to the amplitude of the sound intelligence, and consequently E_o will be frequency modulated by that

50 55 sound.

The condenser C_1 which forms a part of Z_c , and more particularly the charge and discharge rate of that condenser, determines the frequency of the output voltage E_o . It accomplishes this result by modulating the electron flow within the tube V_1 between its cathode 2 and its plate 4, the frequency of this modulation being reflected in a corresponding frequency change at E_o .

As a further and very important feature, it has been found that if the tube control grid G_1 be coupled to any one of the other tube elements, as by Z_g , the effect of variations in E_c on the frequency of E_o is intensified and modified in various ways, depending upon the circuit design. The most marked effect attendant upon this coupling is a highly increased sensitivity of frequency response, that is to say, the curve of frequency against E_c becomes considerably steeper.

In Fig. 1, Z_g is shown as connected to G_2 , but it may instead optionally be connected to any of the other tube elements, different effects being observed in each case. Thus in Fig. 1A Z_g is shown as connected to the anode 4 of the tube, in Fig. 1B Z_g is shown as connected to the screen grids G_3 and G_5 , and in Fig. 11 Z_g is shown as connected to the oscillator control grid G_4 .

The symbols e_{g1} , e_{g2} , e_{g4} and e_p represent respectively the instantaneous values of voltage on G_1 , G_2 , G_4 and plate 4 respectively.

Figs. 2A, 2B and 2C illustrate three suggested circuits for providing the cathode 2 with a bias, best operation of the circuit occurring when such bias is applied. All of these embodiments of Z_k are well-known to the art, and it further will be apparent that if Z_k is omitted, a constant negative bias applied to G_1 will achieve the same end result. In all of the circuits shown in Figs. 9 through 12, a Z_k corresponding to Fig. 2B has been employed, but this is merely a matter of choice.

Figs. 4A, 4B, 4C and 4D are illustrative of some of the various forms which Z_a may take. The presence of C_8 in Figs. 4B and 4D modifies the wave shape of e_{g2} so that, as will be explained, Z_g may cause a phase shift to take place between e_{g1} and e_{g2} . The circuits of Figs. 9 and 11 employ the Z_a of Fig. 4A, while the circuit of Fig. 10 employs the Z_a of Fig. 4B. The circuit of Fig. 12 employs a Z_a different from any of those illustrated in Fig. 4.

Figs. 6A, 6B, 6C and 6D represent various embodiments of Z_o . Figs. 9, 10 and 12 employ the Z_o of Fig. 6A, while Fig. 11 employs the Z_o of Fig. 6D. The latter embodiment defines a parallel resonant circuit having a natural frequency of oscillation. The presence of such a circuit either in Z_o , as in Fig. 11, or in Z_a , as in Fig. 12, has a very marked effect on the operation of the circuit, the current and voltage in the oscillatory circuit assuming a substantially sinusoidal shape, thus facilitating controlled phase shift by Z_g , and the stiffness of the oscillatory circuit modifying the frequency variations of the overall circuit.

Figs. 5A, 5B, 5C and 5D illustrate some of the various forms which Z_c may take. It will be noted that a condenser C_1 is common to all of these forms, this condenser serving to control the frequency of E_o by the time it takes to charge and discharge. In Figs. 9 through 12, the Z_c of Fig. 5A is employed.

Figs. 7A, 7B, 7C and 7D represent some of the various forms which Z_1 may take, this impedance serving not only to bias or apply high positive potential to the tube anode 4, but also serv-

ing to couple the output of the tube V_1 to E_o . The embodiments of Figs. 7A, 7B and 7C employ the capacitive coupling of C_c , while the embodiment of Fig. 7D employs inductive coupling.

Figs. 8A and 8B are illustrative of various embodiments of Z_s , the biasing impedance for the screen grids G_3 and G_5 . In Figs. 9 through 12, the embodiment of Fig. A is used throughout.

The various impedance designs illustrated in the above discussed figures are but typical of circuit designs which may be employed in accordance with this invention. Whichever of the specific embodiments is employed is in many cases a matter of mere choice and circuit design well within the ken of those skilled in the art. This is particularly true with respect to the embodiments of Z_k , Z_s and Z_1 . Certain other of the choices will affect the operation of this circuit in manners hereafter to be described.

The operation of the circuit without Z_g and with G_1 connected directly to E_c will now be described. For purposes of illustration, this description will be carried out with reference to Fig. 9, it being assumed that R_2 is infinite, and that therefore no coupling exists between G_1 and G_2 , and it being further assumed that C_1 and R_3 are absent from the circuit. The oscillatory portion of this circuit is made up by $Z_o(R_g)$, $Z_c(C_1)$, and $Z_a(R_1)$. It will be noted that this oscillatory circuit is made up exclusively of resistive and capacitive elements, this particular circuit arrangement producing at E_o a succession of sawtooth pulses. If C_L be omitted, these pulses will assume a square shape. It will further be assumed that G_1 is at ground potential.

E_b , via R_1 , applies a positive potential to G_2 , and many of those electrons which pass G_1 are attracted to G_2 and impinge thereon, thus decreasing the positive potential of G_2 and consequently decreasing the attraction it exerts on subsequent electrons. These electrons attracted to G_2 pass through R_1 thereby causing a voltage reduction at G_2 which is coupled to G_4 through C_1 causing G_4 to become more negative, G_4 thus decreasing the flow of electrons through the tube to the plate 4, which in turn decreases electron flow through R_L practically to zero so that e_p approaches the value of E_b . When G_2 has accumulated so many electrons that subsequent electrons are no longer attracted to it, the charging of C_1 will cease, and electrons will leave G_4 via R_L , the condenser C_1 thus discharging. The two grids G_2 and G_4 , and particularly G_4 , will therefore each become more positive, and thus the electron flow through V_1 will increase and the current flow through R_L will increase, causing a corresponding decrease in the amplitude of e_p , the variation in e_p being transmitted via C_c to E_o . When G_2 has become positive enough to attract electrons again, the voltage drop through R_1 caused by the leakage of electrons from G_2 will once again cause G_4 to become more negative, and hence the cycle will repeat.

The rapidity with which these cycles occur will be determined by the values of Z_o , Z_c and Z_a , and by the negative transconductance of the tube. The impedances are fixed by circuit design, but the value of transconductance may be varied with E_c , a typical case being illustrated by the lowermost curve of Fig. 18 labeled $R_2 = \alpha$. It will be noted from that curve that as E_c increases (becomes more negative), the value $-R$

increases. $-R$ varies inversely as the transconductance between the grids G_2 and G_4 , and is experimentally determined by decreasing R_g until oscillation just ceases. This variation in $-R$ arises from the tube design, probably in the following manner: As E_c becomes more negative, fewer and fewer electrons are available for passage through V_1 . The smaller the number of electrons available, the less relatively negative must G_2 and G_4 be charged in order to cut off electron flow through V_1 . Hence the fewer the electrons available the lower the potential to which C_1 must be charged in order to cut off electron flow. The lower the potential to which C_1 need be charged, the less time that charging will take up, and the less will be its discharge time. The less the charging and discharging time of C_1 , the more variations will take place in the potential of G_2 and G_4 per unit time, and hence the greater will be the frequency of those oscillations, thus giving rise to an increased frequency in E_o . Thus a variation of E_c varies the transconductance of the tube which varies the charge and discharge rate of the capacitor C_1 , this in turn varying the frequency of output.

The circuit as thus far described therefore provides a simple arrangement in which the frequency of the voltage E_o may be varied merely by changing the voltage E_c .

In order to modify or to intensify this effect, it has been found desirable to impress a voltage e_{g2} , e_{g4} , e_{g5} , or e_p on G_1 . This may be accomplished by addition of impedance elements Z_g to the circuit, this latter impedance serving to couple G_1 with one of the other tube elements. Confining our attention again to Fig. 9, and assuming that $C_7=0$, we find a Z_g employed which corresponds to Fig. 3A. Figs 3B, 3C and 3D represent alternative embodiments for Z_g . Y in these figures represents a connection to any of the other tube elements. Z_g is here shown as coupling G_1 to G_2 . This coupling has the effect, in the circuit now under discussion in which the oscillatory portion of the circuit is composed exclusively of resistive and capacitive elements, of intensifying the effect of E_c on the frequency by what may be termed regenerative action. This is apparent from a study of the family of curves in Fig. 18. It is there seen that as the value of R_2 decreases, thus increasing the coupling effect between the two grids, not only does $-R$ increase for a given value of E_c , thus leading to a higher frequency, but the slope of the curve markedly increases, thus giving rise to a greater change of frequency for a given variation in E_c . This effect occurs because in the circuit now under discussion e_{g1} will be in phase with e_{g2} , and hence e_{g1} will affect the frequency in a way similar to E_c . Thus, comparing curves 1 and 4 of Fig. 14, curve 1 representing a circuit in which e_{g1} is taken from G_2 and curve 4 representing a case in which $e_{g1}=0$, it will be noted that for any given value of E_c the frequency of curve 1 is higher than the frequency of curve 4.

If in this circuit Z_g be connected to G_4 , a different result is observed, such a connection giving rise to a reduction in frequency. Curve 2 of Fig. 14 illustrates this. It is believed that this effect may be explained as follows: Because of the presence of C_1 , the voltage e_{g4} has a wave shape different from e_{g2} , oscilloscope observations indicating that it contains a positive surge immediately following the negative surge. These surges when applied to G_1 apparently reduce electron

70 75

flow while G_2 is attempting to acquire electrons, and to increase electron flow when G_2 no longer can use them. The reduced electron flow increases the time necessary for C_1 to charge G_4 to the value necessary to cut down the later increased electron flow through the tube V_1 . Thus the frequency is decreased.

If Z_g is connected to the tube anode 4 (curve 3 of Fig. 14), the same frequency-decreasing effect is observed as was the case when Z_g was coupled to G_4 , except that the magnitude of the effect is somewhat decreased. This effect also is thought to be due to the variation in wave form between e_p and e_{g2} . Connecting Z_g to the tube anode 4 has been found to have the additional effect of increasing the frequency stability of the circuit, making the oscillator as stable as any good L-C or inverse-feedback stabilized oscillator. It is notable that better amplitude stability is obtained with Z_g coupled to the tube anode 4 (curve 3 of Fig. 13). It will be noted that when e_{g1} is obtained from e_p , the output voltage E_o exhibits less variation than for the other curves, this amplitude stability being equal to that obtained with L-C and stabilized feedback oscillators, while still preserving an excellent ratio of ΔF to ΔE_c . The total output variation is but 40% in spite of the extreme range of frequency control, all of the curves of Fig. 14 having a slope of approximately 8% F_c per volt of E_c where F_c is the center frequency of the linear portion of these curves. Prior systems achieve a slope of approximately 2%, and the improvement which this circuit represents over prior circuits, even when Z_g is omitted (curve 4) will be apparent from this comparison.

Z_g may also be connected to G_5 , the frequency variation effect then approximating that of curve 3 of Fig. 14. However, the wave shape of e_{g5} is apparently such that the amplitude stability achieved when Z_g is connected to the tube anode 4 is not achieved in this case.

In the circuit as thus far described, e_{g1} was effectively in phase with the e_{g2} except when voltages having unusual wave shapes were employed. It has been found that various desirable effects may be produced by forcing e_{g1} out of phase with e_{g2} , either leading or lagging, the effects being different when e_{g1} leads e_{g2} than when it lags. Thus if the Z_o of Fig. 6D be employed in the circuit, this impedance consisting of L_g and C_g connected in parallel, and if Z_a retain the form of Fig. 4A (Fig. 11), or if Z_o takes the form of Fig. 6A while Z_a contains a parallel resonant circuit (Fig. 12), these arrangements being typical of many which could be made in which the oscillatory portion of the circuit has a resonant frequency of vibration so that the current therein and therefore the voltage assumes at least an approximately sinusoidal wave form, e_{g1} may be caused, by Z_g , to differ in phase from e_{g2} . The degree of this phase difference may be controlled at will by design of Z_g in a manner well-known to the art.

When e_{g1} leads e_{g2} , the variations in electron flow past G_2 precede its demand for electrons. Thus when G_2 most wants electrons, the supply of electrons is not maximum, but is decreasing, while when G_2 no longer wants electrons the flow of electrons is increasing. This tends to make Z_c take longer to become fully charged and discharged, since the electrons available during the upswing of each cycle tend to prevent this change in G_2 , while the surge of electrons available during the downswing of each cycle always occurs

ahead of the voltage reduction at G_2 , thereby tending to prevent reduction in e_{g2} . The final result of these trends is to force each cycle to require a longer period, thus resulting in a reduction of frequency.

When e_{g1} lags e_{g2} the effect is just the opposite. The electrons available during the upswing of each cycle are insufficient and hence tend to cause e_{g2} to rise more rapidly, while the increase in available electrons during the downswing of each cycle tends to speed up the reduction of e_{g2} . The final result of these trends is to force each cycle to have a shorter duration, thus leading to an increase in frequency.

The action of E_c in the sinusoidal version of this oscillator now under discussion apparently differs from its action when a pulse-type oscillator in which the oscillatory circuit is composed exclusively of resistive-capacitive elements is employed. Variation of E_c alone without coupling has been found to change the frequency of E_o only very slightly, this probably being due to the stiffness of the oscillatory circuit itself. It is believed that the effect of E_c in this case may be explained as follows: The voltage of G_1 exercises primary control over the number of electrons available for passage through V_1 . As the voltage of G_1 becomes more negative, the number of electrons available decreases, and the speed of those electrons which pass G_1 is also decreased. As E_c and therefore G_1 become more negative, the effect which e_{g1} , the coupled voltage, has on the electron flow through the tube also decreases. In this way E_c controls frequency by control of the per cent modulation due to e_{g1} of the electron stream passing G_1 .

Figs. 15, 16 and 17 illustrate these effects. In Fig. 15, curve 5 represents the results obtained in a circuit in which Z_g corresponds to Fig. 3D (Fig. 12). C_7 , which may either represent a separate circuit element or the inherent interelectrode capacitance of the tube V_1 between G_1 and the cathode 2, further modifies e_{g1} over the effect thereon of the other elements of Z_g . In this case, it is noted that as E_c increases (becomes more negative), the frequency increases. When Z_g takes the form of Fig. 3A (Fig. 11), e_{g1} is caused to lag e_{g2} (see curve 6), and hence as E_c increases (becomes more negative), the frequency decreases. Marked linearity of the curves is obvious.

The circuit constants for the curves of Fig. 15 were so chosen that oscillation took place at relatively low rates ($F_o=126$ kc.). With different circuit constants curves 7 and 8 were developed ($F_o=3525$ kc.), these curves evidencing a very high frequency sensitivity to variation in E_c . Fig. 17 compares curves 9 and 10, somewhat different circuit constants being employed.

All of these curves show a marked linearity over relatively wide variations in E_c , and show exceedingly high frequency sensitivities with regard to variations in E_c .

It will be apparent that in accordance with the considerations above discussed, various specific circuits may be formed from the generic circuit of Fig. 1. By way of exemplification only, and not by way of limitation, four such circuits are illustrated in Figs. 9 through 12. The circuit of Fig. 9 is of the resistive-capacitive, or pulsating type. In this circuit, Z_k takes the form of Fig. 2B, Z_g takes the form of Fig. 3B, Z_a takes the form of Fig. 4A, Z_c takes the form of Fig. 5A, Z_o takes the form of Fig. 6A, Z_s takes the form of Fig. 8B, and Z_l takes the form of Fig. 7A. C_l

causes the pulses of E_o to assume a sawtooth form, and if C_l is omitted those pulses will assume a square shape. C_3 and C_f are bypass condensers.

The circuit of Fig. 10 differs from that of Fig. 9 in omitting C_l and in adding C_8 so that Z_o takes the form of Fig. 4B. The presence of C_8 causes the voltage applied to R_2 to have a modified wave form such that Z_g can impart a phase shift thereto, and therefore by suitable designing Z_g any desired phase shift, and consequently any desired frequency-grid bias relationship may be obtained.

Figs. 11 and 12 are representative of circuit designs in which the oscillatory part of the circuit has a resonant frequency. Fig. 11 shows the resonant circuit, composed of L_g and C_g , as part of Z_o , thus corresponding to Fig. 6D. Fig. 11 also shows G_1 coupled to the oscillator control grid G_4 , the coupling impedance Z_g taking the form of Fig. 3C. Fig. 12 has the resonant circuit portion consisting of $L-C$ as part of Z_a , it being added to the Z_a of Fig. 4B to define a Z_a not elsewhere illustrated in the drawings. A comparison of Figs. 11 and 12 indicates that whether the resonant portion of the circuit forms part of Z_o or Z_a , essentially the same effects are produced, these effects differing in degree and/or sign only, and not in kind.

From the above description, the true flexibility and adaptability of the circuit of the present invention will be apparent. By combining impedances into the arrangement of Fig. 1, the application of a varying voltage E_c to the tube control grid G_1 of tube V_1 , which is biased to a condition of negative transconductance, will so modulate the electron flow through the tube as to cause it to vary at a frequency which itself varies to follow the changes in the voltage E_c . This effect obtains even if Z_g is absent, the presence of Z_g intensifying the effect. It is to be noted that this effect obtains, even though no part of the circuit may be said to have a resonant frequency of vibration. When Z_g is present, it may couple G_1 to any one of the other electrodes of the tube, and when that coupling obtains the output frequency may be controlled by varying either the amplitude, wave form, or phase shift of the coupled voltage e_{g1} , these changes being obtained by choice of proper circuit design in a manner well-known in the art. When the oscillatory portion of the circuit has a resonant frequency, the output frequency may still be varied by changing the voltage E_c .

The circuit here described is of exceedingly high sensitivity, as compared with previous circuits which accomplish the same end, this sensitivity being achieved without loss of high output amplitude stability. The circuit employs but a single vacuum tube, is relatively simple, and requires no critical balancing or high precision of circuit components in order for it to work. It has been observed that the output from this circuit is exceedingly rich in harmonics, thus permitting frequency multiplication by the employment of suitable resonant and trap circuits in the output. This last mentioned factor materially extends the field of applicability of this circuit.

It will be apparent that many variations may be made in the specific circuit design, without departing from the spirit of the invention as set forth in the appended claims.

I claim:

1. A variable frequency oscillator comprising a vacuum tube having as tube elements a cath-

ode, a plate, and at least three intermediate electrodes there-between constituting, in order from cathode to plate, a tube control grid, an oscillator anode, and an oscillator control grid, biasing circuits connected to said tube elements for maintaining said oscillator anode at a higher potential than said tube control grid and said cathode, said plate at a higher potential than any of the other tube elements, and said tube control grid at a potential sufficiently below that of said cathode so that negative transconductance exists between oscillator anode and oscillator control grid, a coupling circuit including a capacitor connected between the oscillator anode and oscillator control grid, a second coupling circuit substantially non-frequency-discriminating over the frequency range of operation of the oscillator and including a capacitor connected between the tube control grid and one of the tube elements other than the cathode and any tube element connected directly to the cathode, and additional means for independently varying the voltage applied to the tube control grid and thereby varying the frequency of oscillation and of said oscillator.

2. The variable frequency oscillator of claim 1, in which the coupling circuit to the tube control grid in conjunction with the biasing circuits for the oscillator anode and the oscillator control grid define a circuit which causes the voltage coupled to the tube control grid to differ in phase from the voltage of the oscillator anode.

3. The variable frequency oscillator of claim 1 in which said second coupling circuit is connected between the tube control grid and the oscillator anode.

4. The variable frequency oscillator of claim 1 in which said second coupling circuit is connected between the tube control grid and said oscillator control grid.

5. The variable frequency oscillator of claim 1 in which said second coupling circuit is connected between the tube control grid and the plate.

6. In the variable frequency oscillator of claim 1, a pair of connected tube elements defining a screen grid on either side of said oscillator control grid, a biasing circuit connected to said screen grid for maintaining it at a potential appropriate for functioning as a screen grid, said second coupling circuit being connected between the tube control grid and said screen grid.

7. The variable frequency oscillator of claim 1, in which the coupling circuit to the tube control grid in conjunction with the biasing circuits for the oscillator anode and the oscillator control grid define a circuit which is composed exclusively of resistive and capacitive elements.

8. The variable frequency oscillator of claim 1, in which the coupling circuit to the tube control grid in conjunction with the biasing circuits for the oscillator anode and the oscillator control grid together include an oscillatory circuit having a resonant frequency of vibration.

9. The variable frequency oscillator of claim 1, in which the biasing circuit for one of the oscillator elements comprises inductive and capacitive elements in parallel.

10. The variable frequency oscillator of claim 1, in which the oscillator circuit is so designed as to impart a substantially sinusoidal shape to the voltage on the oscillator elements and in which the tube control grid is coupled to one of the oscillator elements.

11. The method of varying the frequency of oscillation of the output of a vacuum tube having as tube elements a cathode, a plate, and a plurality

of intermediate electrodes including a tube control grid and oscillator elements including an oscillator anode and an oscillator control grid, said method comprising causing negative transconductance to exist between the oscillator anode and oscillator control grid, maintaining an oscillatory condition between said oscillator anode and oscillator control grid, varying the voltage applied to the tube control grid, and applying to said tube control grid substantially all of the frequency components, within the frequency range of the operation of the oscillator, of the varying voltage of one of said tube elements other than the cathode.

12. The method of varying the frequency of oscillation of the output of a vacuum tube having as tube elements a cathode, a plate, and a plurality of intermediate electrodes including a tube control grid and oscillator elements including an oscillator anode and an oscillator control grid, said method comprising causing negative transconductance to exist between the oscillator anode and oscillator control grid, maintaining an oscillatory condition between said oscillator anode and oscillator control grid, varying the voltage applied to the tube control grid, and applying to said tube control grid the varying voltage of said oscillator anode.

13. The method of varying the frequency of oscillation of the output of a vacuum tube having as tube elements a cathode, a plate, and a plurality of intermediate electrodes including a tube control grid and oscillator elements including an oscillator anode and an oscillator control grid, said method comprising causing negative transconductance to exist between the oscillator anode and oscillator control grid, maintaining an oscillatory condition between said oscillator anode and oscillator control grid, varying the voltage applied to the tube control grid, and applying to said tube control grid substantially all of the frequency components, within the frequency range of the operation of the oscillator, of the varying voltage of said oscillator control grid.

14. The method of varying the frequency of oscillation of the output of a vacuum tube having as tube elements a cathode, a plate, and a plurality of intermediate electrodes including a tube control grid and oscillator elements including an oscillator anode and an oscillator control grid, said method comprising causing negative transconductance to exist between the oscillator anode and oscillator control grid, maintaining an oscillatory condition between said oscillator anode and oscillator control grid, varying the voltage applied to the tube control grid, and applying to said tube control grid substantially all of the frequency components, within the frequency range of the operation of the oscillator, of the varying voltage of said oscillator control grid.

15. The method of varying the frequency of oscillation of the output of a vacuum tube having as tube elements a cathode, a plate, and a plurality of intermediate electrodes including a tube control grid and oscillator elements including an oscillator anode and an oscillator control grid, said method comprising causing negative transconductance to exist between the oscillator anode and oscillator control grid, maintaining an oscillatory condition between said oscillator anode and oscillator control grid, varying the voltage applied to the tube control grid and applying to said tube control grid a varying voltage corresponding to that of one of said tube elements other than the cathode and any tube element connected directly to the cathode but differing in

11

phase therefrom, said varying voltage including substantially all of the frequency components, within the frequency range of operation of the oscillator, of said tube element.

16. The method of varying the frequency of oscillation of the output of a vacuum tube having as tube elements a cathode, a plate, and a plurality of intermediate electrodes including a tube control grid and oscillator elements including an oscillator anode and an oscillator control grid, 10 said method comprising causing negative transconductance to exist between the oscillator anode and oscillator control grid, maintaining an oscillatory condition between said oscillator anode and oscillator control grid, varying the voltage applied to the tube control grid, and applying to said tube control grid a varying voltage corresponding to that of the oscillator anode but differing in phase therefrom.

17. The method of varying the frequency of oscillation of the output of a vacuum tube having as tube elements a cathode, a plate, and a plurality of intermediate electrodes including a tube control grid, a screen grid, and oscillator elements including an oscillator anode and an oscillator control grid, said method comprising causing negative transconductance to exist between the oscillator anode and the oscillator control grid, maintaining an oscillatory condition between said oscillator anode and oscillator control grid, varying the voltage applied to the tube control grid, and applying to said tube control grid a varying voltage corresponding to that of said screen grid.

18. A variable frequency oscillator comprising a vacuum tube having as tube elements a cathode, 35

12

a plate, and at least three intermediate electrodes therebetween constituting, in order from cathode to plate, a tube control grid, an oscillator anode, and an oscillator control grid, biasing circuits connected to said tube elements for maintaining said oscillator anode at a higher potential than said tube control grid and said cathode, said plate at a higher potential than any of the other tube elements, and said tube control grid at a potential sufficiently below that of said cathode so that negative transconductance exists between oscillator anode and oscillator control grid, a coupling circuit including a capacitor connected between the oscillator anode and oscillator control grid, a coupling circuit including a capacitor connected between the control grid and the oscillator anode, and additional means for independently varying the voltage applied to the tube control grid and thereby varying the frequency of oscillation of said oscillator.

WOLCOTT MARSH SMITH.
